UNITED STATES PATENT OFFICE.

FREDERICK BROWNING POTTER, OF NEWARK, NEW YORK.

DESIGN FOR AN INSULATING-BACKPIECE FOR SWITCHES AND ROSETTES.

SPECIFICATION forming part of Design No. 32,880, dated June 26, 1900.

Application filed May 24, 1900. Serial No. 17,890. Term of patent 14 years.

To all whom it may concern:

Be it known that I, FREDERICK BROWNING POTTER, a citizen of the United States, residing at Newark, in the county of Wayne and State of New York, have invented and produced a certain new and original Design for Insulating-Backpieces for Switches and Rosettes; and I do declare the following to be a full, clear, and exact description of the invention, such as will enable others skilled in the art to which it appertains to make and use the same.

The invention relates to a new and original design for insulating-backpieces for switches and rosettes; and it consists of a design of the shape and configuration shown in the accompanying drawings, in which—

Figure 1 is a top plan view, and Fig. 2 is a vertical sectional view, of the design.

The leading feature of the design comprises 20 the annular body portion 1, provided with a central recess 2 and downwardly-extending hollow fingers 3, between which is arranged a central aperture 4, the body portion having, at points diametrically opposite to the aperture 4, apertures 5.

What I claim is—

The design for an insulating-backpiece for switches and rosettes, as herein shown and described.

In testimony whereof I have hereunto set my hand in presence of two subscribing witnesses.

FREDERICK BROWNING POTTER.
